CLAIM

The ornamental design for a tie and handkerchief retail combination, as shown and described.

DESCRIPTION

FIG. 1 is a front elevation view of a tie and handkerchief retail combination showing my new design;
FIG. 2 is a rear elevation view of my design of FIG. 1;
FIG. 3 is a right side view thereof; and,
FIG. 4 is a top plan view thereof.

The tie hanger and rectangular shape shown in broken lines form no part of the claimed design.

The side of the handkerchief shown in broken lines in FIG. 3 illustrates an unclaimed aspect of this feature.
